(57) **CLAIM**

The ornamental design for a pump closure, as shown and described.

DESCRIPTION

FIG. 1 is a perspective view of a pump closure, embodying our new design;

FIG. 2 is a front view of the pump closure of FIG. 1;

FIG. 3 is a back view of the pump closure of FIG. 1;

FIG. 4 is a top view of the pump closure of FIG. 1;

FIG. 5 is a bottom view of the pump closure of FIG. 1;

FIG. 6 is a first side view of the pump closure of FIG. 1; and,

FIG. 7 is a second side view of the pump closure of FIG. 1.

The broken lines shown in the drawings depict environmental subject matter only and form no part of the claimed design.
